Filed Jan. 29, 1968, Ser. No. 10,350

Term of patent 14 years

U.S. Cl. D23—19
Int. Cl. D23—01

FIG. 1 is a front elevational view of a time-controlled valve showing my new design;

FIG. 2 is a top plan view;

FIG. 3 is a rear elevational view thereof;

FIG. 4 is a bottom plan view thereof;

FIG. 5 is an elevational view taken from one side thereof; and

FIG. 6 is an elevational view taken from the side opposite that shown in FIG. 5.

The dominant features of my design reside in the portions shown in full lines, it being understood that the fragmentary broken line representation of tubing and fittings are for purposes of illustration only.

I claim:

The ornamental design for a time-controlled valve, as shown and described.
